(57) **CLAIM**

The ornamental design for a computer screen display or portion thereof with graphical user interface, as shown and described.

DESCRIPTION

The FIGURE is a front view of a computer screen display or portion thereof with graphical user interface showing the new design.

The outermost broken line illustrates the computer screen display, and the broken line showings of text within the outermost broken line illustrate portions of the graphical user interface. None of the broken lines form part of the claimed design.
